CLAIM

The ornamental design for a battery box, as shown and described.

DESCRIPTION

1. Battery box
2. Battery box
- 1.1 : Front
- 1.2 : Back
- 1.3 : Left
- 1.4 : Right
- 1.5 : Top
- 1.6 : Bottom
- 1.7 : Perspective
- 2.1 : Front
- 2.2 : Back
- 2.3 : Left
- 2.4 : Right
- 2.5 : Top
- 2.6 : Bottom
- 2.7 : Perspective

1. Name of the designs: “Battery box”; 2. Use of the designs: battery assembly; 3. Distinctive elements of the designs: the overall shape as shown; 4. Figure best showing the designs:

(Continued)

Perspective views, Figs. 1.1 and 2.1. The broken lines are directed to environment and form no part of the claimed design.
